DRIVING MECHANISM FOR SHAKING CONVEYERS AND THE LIKE

Hans Cremer, Bochum, Germany, assignor to
 Gebrueder Eickhoff, Maschinenfabrik und
 Eisengiesserei, Bochum, Germany

Application December 6, 1934, Serial No. 756,322
 In Germany October 6, 1934

19 Claims. (Cl. 198—220)

My invention relates to shaking conveyers and has in particular reference to the means for driving such conveyers and to means for securing them on the floor in fixed position.

5 My invention has for one of its objects a drive for shaking conveyers in which a rotary motor, in particular an electric motor, is made use of and in which the point or points of application of the driving force are situated at a low level and symmetrically to the central line of the conveyer. These conditions are as yet not fulfilled in the known electric twin drives in which swing levers are provided on both sides as well as cranks and rods which are applied below the conveyer to the latter, whereby a correspondingly high position of the conveyer above the floor is required on the point of application of these parts. In addition, delicate parts of the gear, viz. the cranks, lie free in the construction, 10 which is a drawback.

20 Now the drive for shaking conveyers according to my invention, which is fitted with a rotary motor, is characterized by the feature, that the portion of the gear adjacent to the driving motor comprises a member which determines the law of motion of the conveyer and is lodged in a casing portion situated beside the conveyer, and further, that the transmission of the motion of the motor to the conveyer is established by one or two cranks, in the latter case arranged as twin cranks, with coupling rods and reciprocating rods. These parts are lodged in a casing which is closed except one sole passage for the respective reciprocating rod. Such a 25 gear has at least partially a very small structural height, so that the conveyer itself can be disposed at a very low level above the lower portion of the casing. The described construction affords the advantage that the parts of the gear 30 can be enclosed in a casing which, except the passages for the reciprocating rods, is entirely closed, the passages for the rods being packed by stuffing boxes, so that no delicate articulated or rotary parts exist outside the casing. As a 35 consequence of the described construction the member which determines the law of motion of the conveyer may be designed as a separate driving unit, which is of importance for the drive of shaking conveyers of small structural 40 length. To this end this gear part together with the appurtenant casing portion may be constructed so as to be detached from the remaining gear parts and casing portion, a suitable cover being provided for the surface of 45 separation.

Another object of the present invention resides in securing the gear mechanism to the floor and maintaining it without injury to the supporting structure of the individual gear parts.

5 Prior to the present invention, gear mechanisms for shaking conveyers were usually secured to the floor by props which were wedged between the roof and the gear, its support or casing so as to press directly on these elements. The wedging action of the props, however, has 10 the tendency to distort these elements, to affect the position of the gear parts relative to each other and to injure the entire mechanism. This disadvantage may be overcome by securing a 15 separate element fixedly to the floor and connecting the gear mechanism thereto.

Although some of the above disadvantages are overcome by this procedure, other distorting movements are transmitted to the gear and its casing, which are caused by the leverage arising 20 between the point where the props engage the securing element and the place where the conveyer is connected to the gear. These movements easily cause the operators of the conveyer to secure the gear casing not only indirectly by means of the securing element, but also 25 directly by props.

It is therefore another object of the invention to connect the securing element rigidly with the gear casing at least substantially aligned 30 with the coupling member connecting the gear with the conveyer, or at least substantially symmetrical relative to this member, or at least substantially at the same height as this member. By such a construction any leverage between the 35 gear and the securing element is substantially avoided so that the gear casing rests immovably on the floor, although fixed to the securing element only by means of the rigid connection, and any occasion for securing the gear casing directly 40 also is avoided.

A still further object resides in a light and easily movable construction. Since the gear casing is secured at least substantially without leverage, only that part of the casing needs to be 45 reinforced which is located between the point of engagement of the securing elements on the gear casing and the point where the coupling member connecting the gear with the conveyer engages the gear. Only within this area can 50 the gear casing be affected by the conveying forces and this effect is considerably reduced according to the invention by arranging these points of engagement closely adjacent each other 55 on the casing. All the other parts of the gear

casing need only be sufficiently strong to withstand the forces arising in the gear bearings.

Still another object resides in further elimination of the forces affecting the gear casing 5 and the gear by guiding the conveyer trough on the gear casing or on the securing element or on both, in a straight direction. By this arrangement the coupling member connecting the gear with the conveyer may be guided also outside of 10 the gear casing.

In order that my invention may be clearly understood and readily carried into effect, some embodiments of the same are illustrated by way 15 of example in the accompanying drawings, in which

Figure 1 is an end view of the first embodiment of my new shaking conveyer drive,

Figure 2 is a top view thereof,

Figure 3 is an end view and Figure 4 a top 20 view of a second embodiment,

Figure 5 is a sectional view of the third embodiment,

Figure 6 is a sectional top view thereof,

Figure 7 is a sectional view of the fourth modification,

Figure 8 is a sectional top view thereof,

Figure 9 is a sectional view of a fifth modification, and

Figure 10 is a diagrammatic side view thereto.

In the embodiment illustrated in Figures 1 and 2 a rotary motor, e. g. an electric motor 1 is connected by intermediate spur wheel gears 2, 3, 4, 5 to a pair of bevel wheels 6, 7 the horizontal wheel 7 having rigid to it an elliptic wheel 8 which is mounted above or below the former and revolves about one of its foci. This elliptic wheel is in mesh with a horizontal companion elliptic wheel 9 likewise revolving about one of its foci and having fast to it a crank 10 which by a rod 11 is connected to a reciprocating rod 12. The whole gear is enclosed in a casing g which has a comparatively small structural height except its portion containing the gear parts 2, 3, 4, 5, since its remaining portion includes only horizontally disposed spur wheels. Merely the reciprocating member 12 extends through the wall of the casing g and its passage opening is packed by means of a stuffing box (not shown). The outer end of the member 12

40 is connected with a movable bridge part 20' of the conveyer mounting symmetrically about at the level of the bottom of the conveyer trough r. The bridge part 20' in its turn is rigidly connected to the trough r. The base plate 21' of the mounting is connected by rods 22' with the casing g so as to withstand draw and buffing forces, the rods 22' preferably being disposed about at the level of the reciprocating rod 12, so that the couples of forces on both sides acting on the casing are fully balanced and no external tilting moments act upon the latter. If, further, the base plate 21' of the mounting is fixed in position by means of foundation screws 23' or the like, then owing to said forces being balanced no special fixation of the gear casing is required. This feature, in its turn, affords the advantage, that the gear casing is not stressed by external distorting forces that would 55 impair the correct mesh of the gear parts.

In the modified drive illustrated in Figures 3 and 4 the spur wheel gear 2 driven by the rotary motor 1 and intermediately connected with the spur wheels 3, 4, 5, the bevel wheels 6, 7, the elliptic wheels 8 and 9, the crank 10, the rod 11

and the reciprocating member 12 are arranged in the same manner as in the drive shown in Figures 1 and 2. The elliptic wheel 9 has further rigid to it a spur wheel 13 which through intermediate wheels 14, 15 is in mesh with a spur wheel 16 in such a manner that no gearing up or down exists between the wheels 13 and 16 which thus revolve at the same rate of revolution. The spur wheel 16 has rigid to it a crank 17 which by a coupling rod 18 is in connection with a second reciprocating member 19. The whole gear is enclosed in a casing g, g¹, g the central portion g¹ of which, as it will be seen best in Figure 3, has a still somewhat smaller structural height than the two side portions, so that the casing has a U-shaped sectional form. The central casing portion g¹ has such a width that the conveyer may be disposed above this portion and, more particularly, in such a manner, that the upper edges of the trough lie at least approximately flush 20 with the upper surface of the two lateral casing portions.

The connection between the two sides of the described twin gear may be effected further by one sole big spur wheel 24, as marked by a dot and dash circle in Figure 4, instead of by two or more intermediate spur wheels 14, 15. This would, however, not be so advantageous, since one sole spur wheel not only occupies more space than a couple of wheels, but also, further, by the provision of couples of wheels between the two sides of the twin gear symmetrical opposite directions of revolution of the two crank gears are obtained, which results in an adequate balance of the masses and forces.

In the modified drive illustrated in Figures 5 and 6 the motion of the rotary motor 1' is transmitted to a horizontal crank shaft 36 by means of vertical spur wheels 30, 31, 32, 33 and a pair of vertical elliptic wheels 34, 35 which each are mounted for rotation about one of their foci. The crank shaft 36 on its ends carries symmetrically arranged cranks 37 and 38, which overhang and transmit their motion through rods 39, 40 to reciprocating plungers 41, 42 which like 45 in the first embodiment are connected to the movable bridge part 20 of the conveyer mounting. The base plate 21 is again fixed by means of props 43 and connected to the casing g, g¹, g by connecting rods 44. As to be seen in Figure 50 3, also this casing has a central lower portion g¹ above which the conveyer trough is arranged at a comparatively low level. As in the first embodiment the casing g, g¹, g is entirely closed and has only the two passages for the reciprocating plungers 41, 42.

In the embodiment illustrated in Figures 7 and 8 the rotary motor 1" transmits its motion through pairs of intermediate spur wheels 50, 51 and 52, 53 to a shaft 54 that carries an elliptic 60 wheel 55 which turns about one of its foci and is in mesh with a similarly mounted elliptic wheel 56 which has rigid to it a spur wheel 57 and a crank 58. Spur wheel 57 is in mesh with a pinion 59 mounted on a quickly revolving intermediate shaft 60 which is arranged at a low level and on its other end carries a pinion 61 similar to pinion 59 and in mesh with a spur wheel 62 driving the other crank 63. The two cranks rest in the outer walls of the casing parts g. The reciprocating 70 plungers 64 and 65 tightly pass through the casing and are connected by rods 66 with the movable bridge part 20 of the conveyer mounting. The base plate 21 of the latter is connected to the casing parts g, g by rods 67. The central por- 75

- tion g^1 of the casing may be made extremely low, as shown in Figure 5, so that in this case the conveyer trough r may be arranged at a particularly low level above the central casing portion g^1 .
- 5 Both in the embodiment of Figures 3 and 4 and in that of Figures 5 and 6 the casing g , g^1 , g , like in the first described embodiment, Figures 1 and 2, is subdivided vertically in such a manner, that the casing portion, which is adjacent to the driving motor and encloses the gear part determining the law of motion of the conveyer and the one crank and reciprocating rod, is separated from the remaining casing portion and the gear parts therein and, when separated, can be closed 10 by a lateral cover. Consequently, in all embodiments, the gear part that prescribes the law of motion of the conveyer may be used together with the motor as a conveyer driving unit in connection with any other conveyer.
- 10 In lieu of using a pair of elliptic spur wheels in order to obtain a favorable law of motion of the conveyer other suitable means may be employed in all embodiments described, such as an elliptic wheel which is in mesh with an eccentric 15 circular wheel, with an average ratio of transmission of 2:1, or toggle wheel gears. Figures 9 and 20 show a gear of this latter type.
- The intermediate shaft 14, which is driven by the intermediate wheels 10, 11, 12, 13, has rigid 25 to it a pinion 15 which through an intermediate wheel 16 drives an eccentrically mounted wheel 17. The distance between the centers of pinion 15 and intermediate wheel 16 is secured by two arms 18 swingingly mounted on the shaft 14 on 30 both sides of pinion 15, while another pair of arms 19 secures the distance of the center of the intermediate wheel 16 from the center of the crank wheel 11. In this manner both pairs of arms 18, 19 are hingedly mounted on the intermediate shaft. The eccentric wheel 17 has likewise rigid to it a crank pin 80 for the conveyer drive which, as to the rest, consists again of reciprocating plungers 81 etc. The eccentricity is marked by e , Figure 10. It does not correspond as 40 to its length and position to the radius of the crank.
- 45 What I claim as my invention is:—
1. A drive for a shaking conveyer, comprising a rotary motor, a gear, a crank actuated by said gear, a coupling rod connected to said crank and a reciprocating member connected to said coupling rod, a casing enclosing said gear and closed except an opening for said reciprocating member, a conveyer base plate adapted to be fixed in 50 position and connected to said casing so as to withstand draw and buffing forces, a transverse bridge shiftable on said base plate and carrying the conveyer trough and connected to said reciprocating member.
2. A drive for a shaking conveyer, comprising a rotary motor, a gear, spur wheels in engagement with said gear, a pair of elliptic wheels driven by said spur wheels and each mounted for rotation about one of its foci, a crank driven from 55 one of said elliptic wheels, a coupling rod connected to said crank, a reciprocating member connected to said coupling rod, a casing enclosing said crank gear and closed except an opening for said reciprocating member, a conveyer base plate adapted to be fixed in position and connected to said casing so as to withstand draw and buffing forces, a transverse bridge shiftable 60 on said base plate and carrying the conveyer trough and connected to said two reciprocating members.
3. A drive for a shaking conveyer, comprising a rotary motor, a gear, a crank actuated by said gear, a coupling rod connected to said crank and a reciprocating member connected to said coupling rod and to the conveyer trough, a casing enclosing said gear and closed except an opening for said reciprocating member, means interposed between said motor and said crank for producing a reciprocatory conveying motion required for the shaking conveyer, the drive further comprising another crank gear with reciprocating member arranged symmetrically with the first-named crank gear and reciprocating member, intermediate gear members interconnecting said two crank gears and adapted to set them in opposite motion 10 rotating in synchronous phase, and a casing enclosing said other gear parts and closed except an opening for said other reciprocating member, said casing being connected with the first-named casing. 20
4. A drive for a shaking conveyer, comprising a rotary motor, a gear, a crank actuated by said gear, a coupling rod connected to said crank and a reciprocating member connected to said coupling rod and to the conveyer trough, a casing enclosing said gear and closed except an opening for said reciprocating member, means interposed between said motor and said crank for producing a reciprocatory conveying motion required for the shaking conveyer, the drive further comprising another crank gear with reciprocating member arranged symmetrically with the first-named crank gear and reciprocating member, intermediate gear members interconnecting said two crank gears and adapted to set them in opposite motion 25 rotating in synchronous phase, and a casing enclosing said other gear parts and closed except an opening for said other reciprocating member, a wholly closed third casing enclosing said intermediate gear members and interconnecting 30 said two other casings, said third casing having a smaller structural height than the former and being of a width so as to permit the conveyer trough to be disposed above it and being approximately flush with the upper edges of said two 35 other casings. 40
5. A drive for a shaking conveyer, comprising a rotary motor, a gear, a crank actuated by said gear, a coupling rod connected to said crank and a reciprocating member connected to said coupling rod, a casing enclosing said gear and closed except an opening for said reciprocating member, the drive further comprising another crank gear with reciprocating member arranged 55 symmetrically with the first-named crank gear and reciprocating member, intermediate gear members interconnecting said two crank gears and adapted to set them in opposite rotary motion, and a casing enclosing said other gear parts and closed except an opening for said other reciprocating member, said casing being connected with the first-named casing, a conveyer base plate adapted to be fixed in position and connected to said casings so as to withstand draw and buffing forces, a transverse bridge shiftable 60 on said base plate and carrying the conveyer trough and connected to said two reciprocating members. 65
6. A drive for a shaking conveyer, comprising a rotary motor, a gear, spur wheels in engagement with said gear, a pair of elliptic wheels driven by said spur wheels and each mounted for rotation about one of its foci, a crank driven from one of said elliptic wheels, a coupling rod connected to said crank, a reciprocating member 70 connected to said coupling rod, a casing enclosing said crank gear and closed except an opening for said reciprocating member, a conveyer base plate adapted to be fixed in position and connected to said casing so as to withstand draw and buffing forces, a transverse bridge shiftable 75 on said base plate and carrying the conveyer trough and connected to said reciprocating member. 75

- connected to said coupling rod and to the conveyer-trough, and a casing enclosing said crank gear and closed except an opening for said reciprocating member, said drive further comprising another crank gear with reciprocating member arranged symmetrically with said first-named crank gear and reciprocating member, intermediate gearing means interconnecting said two crank gears and adapted to set them in opposite rotation, and another casing enclosing said other crank gear and member and closed except an opening for said reciprocating member, said other casing being detachably connected to said first-named casing.

15. 7. A drive for a shaking conveyer, comprising a rotary motor, a gear, spur wheels in engagement with said gear, a pair of elliptic wheels driven by said spur wheels and each mounted for rotation about one of its foci, a crank driven from one of said elliptic wheels, a coupling rod connected to said crank, a reciprocating member connected to said coupling rod and a casing enclosing said crank gear and closed except an opening for said reciprocating member, said drive further comprising another crank gear with reciprocating member arranged symmetrically with said first-named crank gear and reciprocating member, intermediate gearing means interconnecting said two crank gears, and adapted to set them in opposite rotation, and another casing enclosing said other crank gear and rod and closed except an opening for said reciprocating member, said other casing being detachably connected to said first-named casing, a conveyer base plate adapted to be fixed in position and connected to said casings so as to withstand draw and buffing forces, a transverse bridge shiftable on said base plate and carrying the conveyer trough and connected to said two reciprocating members.

30. 8. A drive for a shaking conveyer according to claim 2 in which some of said spur wheels of said gear are arranged so as to revolve in a horizontal plane.

45. 9. A drive for a shaking conveyer comprising a driving gear for producing a reciprocatory conveying motion, a casing, said gear being secured to said casing and enclosed thereby, means for coupling said gear to said conveyer so as to transmit the conveying motion to said conveyer, means for securing said casing comprising a member fixedly secured to the ground and elements connecting said casing to said member and exerting a force substantially parallel with, and in the same plane transverse to the longitudinal vertical plane of the conveyer as, the force exerted by said coupling means on the gear, so as to withstand draw and buffing forces between said gear, said casing, and said member.

60. 10. A drive for a shaking conveyer comprising a driving mechanism for producing a reciprocatory conveying motion, means for securing said mechanism comprising a support for said conveyer fixedly secured to the ground and elements connecting said mechanism to said support, means for coupling said mechanism to said conveyer so as to transmit the conveying motion to said conveyer, said coupling means being arranged intermediate said connecting elements so as to withstand draw and buffing forces between said mechanism and said support.

65. 11. A drive for a shaking conveyer comprising a driving gear for producing a reciprocatory conveying motion, a casing, said gear being secured to said casing and enclosed thereby, means

70. 12. A drive for a shaking conveyer comprising a driving mechanism for producing a reciprocatory conveying motion, means for securing said support for said conveyer fixedly secured to the ground and elements connecting said casing to said support and exerting a force substantially parallel with, and in the same plane transverse to the longitudinal vertical plane of said conveyer as, the force exerted by said coupling means on the gear, so as to withstand draw and buffing forces between said gear, said casing, and said support.

75. 13. A drive for a shaking conveyer according to claim 9 including a transverse bridge, said coupling means being connected to said bridge for transmitting the conveying motion thereto, a conveyer trough supported by said bridge, and means on said member for guiding said bridge.

80. 14. A drive for a shaking conveyer according to claim 9, said driving mechanism comprising a driving gear, a pair of reciprocating members, a pair of cranks, and a pair of connecting rods connecting said cranks with their corresponding reciprocating members each of said pairs being arranged symmetrically with respect to said conveyer, means intermediate said cranks connecting said cranks to each other, means for guiding said reciprocating members in straight direction and parallel to one another, and a casing completely enclosing said driving mechanism and having openings for the passage of said reciprocating members.

85. 15. A drive for a shaking conveyer comprising a unit including a rotary motor, means for converting the rotary motion produced by said motor into a reciprocatory conveying motion including a crank gear actuated by said means, a reciprocating member connected to said crank gear, and means for guiding said reciprocating member in a straight direction, a second unit comprising a second crank gear similar to said first gear, means for transmitting the motion of said first gear uniformly to said second gear, a second reciprocating member connected to said second crank gear, and means for guiding said second reciprocating member in a straight direction and parallel to said first reciprocating member, a casing enclosing each of said units, each casing having an opening at one side for connecting said transmitting means to said first crank gear and means for sealing said casings together when said two units are used together, and means for closing the opening in the casing of said first unit when said first unit is to be used individually, each of said casings having another opening for the passage of said reciprocating members.

90. 16. A drive for a shaking conveyer including a driving gear, a crank, a driven gear connected to but mounted eccentrically with respect to the

axis of rotation of said crank, and an intermediate gear connecting said driving with said driven gear, said intermediate gear being hinged-
ly secured to the shafts of both said driving and
5 driven gears.

17. A drive for a shaking conveyer comprising
a driving mechanism for producing a reciproca-
tory conveying motion, means for securing said
10 mechanism comprising a support for said con-
veyer fixedly secured to the ground and elements
connecting said mechanism to said support,
means for coupling said mechanism to said con-
veyer so as to transmit the conveying motion to
15 said conveyer, said coupling means being ar-
ranged intermediate said connecting elements,
said connecting elements being arranged relative
to each other so that the forces exerted by said
connecting means on said mechanism in verti-
cal planes are in equilibrium.
- 20 18. A drive for a shaking conveyer comprising
a driving mechanism for producing reciproca-
tory conveying motion, means for securing said
mechanism comprising a support for said con-
veyer fixedly secured to the ground and elements
25 connecting said mechanism to said support,

means for coupling said mechanism to said con-
veyer so as to transmit the conveying motion to
said conveyer, said coupling means being ar-
ranged intermediate said connecting elements,
said connecting elements being arranged relative
5 to each other so that the forces exerted by said
connecting means on said mechanism in hori-
zontal planes are in equilibrium.

19. A drive for a shaking conveyer comprising
a driving gear for producing a reciprocating con-
veying motion, a casing, said gear being secured
to said casing and enclosed thereby, means for
securing said casing comprising a support for
10 said conveyer fixedly secured to the ground and
elements connecting said casing to said support,
means for coupling said gear to said conveyer so
as to transmit the conveying motion to said con-
veyer, said coupling means being arranged inter-
mediate said connecting elements, said connect-
ing elements being arranged relative to each 15
other and to said coupling means so that the
forces exerted by said connecting elements and
coupling means on said casting are in equi-
librium.

HANS CREMER. 25
